UNITED STATES PATENT OFFICE

JOHN D. McEWEN, OF PITTSBURGH, PENNSYLVANIA, ASSIGNOR TO LEE C. MOORE & COMPANY, INCORPORATED, OF PITTSBURGH, PENNSYLVANIA, A CORPORATION OF PENNSYLVANIA

CLAMP FOR DERRICKS

Application filed April 30, 1927. Serial No. 188,026.

This invention relates to clamps for tubular leg members of metal derricks, particularly those used for drilling and operating oil wells, and the like.

5 The objects of the invention are to improve the construction of such clamps. The improvements comprise better arrangement and construction of parts giving greater strength without increase of weight and 10 greater convenience in fabrication and application.

Referring to the drawings, Fig. 1 is a plan view of a clamp as applied to the top of a tubular leg section; Fig. 2 is a section of the 15 clamp only on the line II—II of Fig. 1; and Fig. 3 is a perspective view of the clamp as applied to adjoining tubular sections, with other portions of the derrick structure indicated as applied thereto.

20 As is well known in this art, all-metal derricks for oil well drilling and the like, are largely employed. They usually consist of four corner columns or legs, formed by end to end coaxial tubes, the adjoining ends of the 25 tube sections being connected together by clamps, and the corner columns being connected to each other by cross girts and braces, for the purpose of forming the whole into a strong self-supporting structure.

30 Such derricks are well known in this art, and therefore no general illustration or description thereof is necessary to an understanding of this invention by those skilled in the art.

35 Referring to Fig. 3, a clamp is illustrated as applied to adjoining tubular leg sections 1 and 2, with diagonal braces 3 and 4, and a horizontal girt 5 attached as in the completed derrick.

40 The clamp comprising the present invention is made of a single piece of plate metal, forged to final shape by suitable punching, die, and pressing operations. When completed the clamp C is bent to circular form, the diameter of the inside of the clamp being 45 slightly larger than the external diameters of the leg sections 1 and 2 that are to be connected by the clamp. The edges of the clamp are turned outward to form flanges 10 and 11, as indicated in Fig. 1. These are not normal-

ly in contact with each other, having a gap between, so that compression bolts 12a may be applied to these flanges to constrict the clamp, whereby to draw the clamp tightly into contact with the ends of the tubular section when positioned therein as indicated in Fig. 3, so as to rigidly and permanently engage them under normal conditions.

45 From the main body portion of the clamp upper ears 12, intermediate ears 13, and lower ears 14, are struck up, on each side of the clamp. These ears or flanges have suitable perforations 15 for receiving bolts 16 adapted to pass therethrough and through the ends of the respective connecting girts and braces 50 3, 4 and 5, as indicated in Fig. 3.

55 Adjoining ends of tubular sections 1 and 2 are each adapted to extend to the median transverse plane of the clamp, and to abut end to end in the line of that plane, as indicated in Fig. 3. Positioned above and below the median plane, respectively, are diametrically oppositely positioned pairs of bolt holes 20, 20, and 21, 21, respectively. These are adapted to receive transverse bolts 23 and 22, respectively, which are adapted to extend through the walls of the clamp, and through the walls of the adjacent tubular sections respectively, near their ends, as shown in Fig. 3. These bolts furnish a positive lock of the 60 tubular sections in the clamp, as will be apparent. They also reinforce the gripping action of the clamp upon the tubular sections, and furnish a safe-guard against the pulling out of the tubular sections, due to wind 65 strains, or other causes. The perforations 20, 20, and 21, 21 are positioned at points where they will least weaken the body structure of the clamp.

70 The ears 12, 13, and 14 are in two similar sets, those of each set lying in a common diametrical plane. The two sets of ears are struck up from the plate from portions thereof unsymmetrically positioned with respect to the edge flanges 10 and 11. One set of ears, 75 shown at the lower corner of Fig. 1, is struck up from metal near terminal flange 10, while the other set of ears is struck up from metal diametrically opposite and comparatively 80 more remote from edge flange 11. As a re-

sult of this shifting of the ears to unsymmetrical position relative to the edge flanges, the diametrical plane between the edge flanges will not coincide with the diametrical plane between the ears. This unsymmetrical position provides ample room for bolt holes adjacent the base of edge flange 11, which would not otherwise be available.

These transverse bolts 22 and 23 are further of great convenience in assembling the clamp and the tubular sections, since the clamp may be placed upon the upper free end of a lower tubular section 1, and the lower bolt 22 put through the holes 21, 21 and through corresponding holes in the upper end of the tubular section 1, thus serving preliminarily to position and hold the clamp in place while the other tubular section 2 is being brought into position. This is of great convenience, since it permits a ready preliminary positioning and holding of the clamp upon the end of the one tubular section, without the necessity of tightening the bolts 12a. Where it is necessary to tighten these bolts in order to hold the clamp in position upon the first tube section that necessarily renders it somewhat difficult to insert the other tubular section of the leg in the clamp and to lower it to final position therein.

It will be further observed that the bolts 22 and 23 seat at both ends upon the body of the clamp, that they not only positively lock the ends of the tubular sections in the clamp, but they serve to squeeze the walls of the clamp together, and thus reinforce and add to the constricting effect of the bolts 12a.

The clamp has advantages of structure that will be apparent to those familiar with this art.

I claim:

1. In the art of metal derricks for oil well drilling and the like, a clamp for connecting adjacent aligned sections of tubular derrick legs comprising a single metal plate bent to circular form with the meeting edges turned out to form substantially parallel flanges extending longitudinally the full length of the clamp, said flanges being perforated to receive compression bolts whereby to constrict the clamp to grip the ends of tubes inserted therein, and perforated ears struck up from the body of the plate and positioned for attachment to girts and braces of a derrick structure, the clamp having oppositely disposed perforations on each side of a median transverse plane positioned and adapted to receive transverse diametric bolts extending through the two walls of the clamp and through the ends of adjoining tube sections, whereby to attach the clamp to each of the adjoining tube sections and to rigidly connect them to each other, said ears being so positioned that a diametrical plane therebetween will not coincide with a diametrical plane between said flanges, whereby to pro-

vide maximum space for said through bolt holes in the body of the clamp.

2. In the art of metal derricks for oil well drilling and the like, the combination of tubular sections adapted to be joined end to end to form a leg of a derrick, the ends of the sections having diametrically opposite perforations, a clamp adapted to engage and connect the adjacent ends of two such sections, the clamp consisting of a metal plate bent to circular form slightly larger in diameter than the tubular sections and having its longitudinal edges turned outward to form spaced apart substantially parallel flanges having perforations adapted to receive compression bolts whereby to constrict the clamp to grip the tubular section ends, two sets of ears struck up from the body of the clamp remote from the edges thereof and positioned substantially at right angles to each other, the ears being perforated to receive bolts whereby to attach the usual girts and braces of derrick structures, the clamp having perforations diametrically oppositely disposed in pairs respectively above and below its median transverse plane and adapted to receive bolts passing through the ends of the tubular sections held by the clamp, the ears being unsymmetrically positioned with respect to the flanges, whereby to provide maximum room for the said through bolt holes.

3. A clamp for tubular leg sections of well-drilling derricks formed from a single plate bent to cylindrical shape with terminal outward flanges opposed and perforated to provide means for compressing the clamp on the tubular sections, and two sets of intermediate ears struck up from the body of the plate leaving openings between the ears and said flanges and perforated to receive bolts for attachment of girts and braces thereto, one set of said ears being struck up from metal near one of said terminal flanges, the other set of ears being struck up from metal diametrically opposite that of the first mentioned ears and comparatively more remote from the other terminal flange, the plate between the last mentioned set of ears and flange being perforated immediately adjacent one of said flanges, and the metal between said ears and immediately adjacent the bases of the first mentioned set of ears being perforated to receive through bolts adapted to pass diametrically through the clamp and leg sections enclosed therein.

In testimony whereof, I sign my name.
JOHN D. McEWEN.
